United States Patent Office

Des. 230,630
Patented Mar. 5, 1974

230,630

ELECTRICALLY POWERED MEAT SLICER

Daniel E. McCue, Santa Barbara, Calif., assignor to Rival
Manufacturing Company, Kansas City, Mo.

Filed Jan. 21, 1972, Ser. No. 219,917

Term of patent 14 years

Int. Cl. D15—08

U.S. Cl. D55—1 A

Fig. 1.

Fig. 2.

*Fig. 3.**Fig. 5.*

FIG. 1 is a front elevational view of an electrically powered meat slicer showing my new design;

FIG. 2 is a top plan view thereof;

FIG. 3 is a rear elevational view thereof;

FIG. 4 is an end elevational view thereof from the left of FIG. 1; and

FIG. 5 is an end elevational view thereof from the right of FIG. 1.

I claim:

The ornamental design for an electrically powered meat slicer, as shown.
